UNITED STATES PATENT OFFICE.

JOSEPH G. COFFIN, OF HEMPSTEAD, NEW YORK, ASSIGNOR TO THE GENERAL RUBBER COMPANY, OF NEW YORK, N. Y., A CORPORATION OF NEW JERSEY.

DRYING APPARATUS.

Application filed April 30, 1923. Serial No. 635,535.

To all whom it may concern:

Be it known that I, JOSEPH G. COFFIN, a citizen of the United States, residing at Hempstead, Long Island, county of Nassau, State of New York, have invented a certain new and useful Improvement in a Drying Apparatus, of which the following is a full, clear, and exact description.

This invention relates to a drying apparatus, more particularly to an apparatus by which rubber latex or similar material may be dried while in a finely divided form.

At the present time the bulk of the world's rubber is made from latex obtained from cultivated trees, and the ordinary method employed for obtaining the crude rubber from the latex is to coagulate the latter by some material such as acetic acid, the coagulated latex then being dried, and otherwise prepared for the market. Methods and apparatus have been devised for obtaining rubber from the latex by finely dividing the latter and drying the particles while in suspension in a drying medium, the precipitated and agglomerated dried particles being then compacted to form crude rubber. Patent to Bradley & Coffin, No. 1,428,526, dated September 12, 1922, is for a method and apparatus for obtaining dried rubber latex or similar materials in this manner, and the present invention aims generally to provide improvements over the above-mentioned apparatus by which the capacity may be increased, and economy, an improved product, and protection of the operatives from excessive heat may be obtained.

An object of the invention is to provide a latex drying apparatus capable of continuous operation.

Another object is to provide an improved means for collecting and removing the dried latex from the drying chamber.

Still another object is to provide an improved form of drying chamber.

A further object is to provide means for protecting the operative from heat effects during removal of the dried product, during an interchange of parts, and generally during the operation of the device.

Still another object is to provide an improved exhaust apparatus for the drying medium by which the carrying off of dried latex particles is substantially prevented.

Still another object is to provide a means

for readily exchanging the latex comminuting device when desired.

For a detailed disclosure of the nature and objects of the invention, reference is had to the accompanying specification and drawings in which latter:

Fig. 1 is a plan view partially in section of the drier,

Fig. 2 is an elevation partially in section with parts omitted for the sake of clearness,

Fig. 3 is an enlarged sectional detail illustrating the exhaust and collecting means for the drying medium,

Fig. 4 is a diagrammatic view illustrating the construction of the movable dried latex collecting platform and one form of mechanism for moving it,

Fig. 5 is an enlarged sectional detail illustrating the mechanism for quickly exchanging the spray unit and for protecting the operative during such exchange,

Fig. 6 is a detail of a closure used, and

Fig. 7 is a detail of the mechanism for removing the spray unit.

Referring to Figs. 1 and 2, the numeral 1 designates the drying chamber generally, the latter being formed with side walls 2 tapering to the top 3. In the present instance the side walls and top are shown as made of reinforced concrete on account of its permanence, weather resisting and natural heat insulating qualities and its air tightness, but any other suitable material may be used. As the greatest heat is developed adjacent the upper portion of the drying chamber and the drying is largely completed there the lower portion of the wall 2 may, if desired, be made entirely of the reinforced concrete, but the upper portion is preferably formed with a heat insulating layer 4 of the material known as "celite", or any other suitable material, the latter being covered with a layer 5 of hollow tile and an outer coating 6 of cement. The top 3 is also provided with a layer 4 of the heat insulating material which is covered with a layer 6 of cement. At the bottom the drying chamber in the present instance is made of square form, and the side walls 2 gradually merge to a polygonal form having a greater number of sides than a square, in the present instance to that of an octagon, at the top. On the top is disposed a housing 7 which may be made of any suitable material such as hollow tile and concrete, and access to this

100

105

110

housing may be had by means of a stairway 8. At a point approximately centrally of the top it is formed with a depression 9 which may be of a frusto-conical form, and in the bottom wall of the depression an opening 10 is formed in which may be disposed a readily removable sprayer 11 of the centrifugal type and having a rotatable spraying disc 12 to which the latex or other material to be sprayed is supplied. This sprayer is preferably made as a unit having a self-contained motor for driving the disc 12 and may be of any suitable type, such as that shown in co-pending application, Serial No. 635,536, filed April 30, 1923. Disposed on the top 3 within the housing is a tank 13 for the latex which may be supplied in any suitable manner and is provided with any suitable quick-detachable connections with the sprayer 11.

Also disposed on the top 3 is a furnace 14 provided with a burner 15 to which fuel may be supplied by the pipe 16 leading from the tank 17. Air for comminuting the fuel may be supplied to the burner by the pipe 18 from either of the duplicate blowers 19. The construction of this furnace is in general similar to that disclosed in the before-mentioned patent to Bradley & Coffin, but the mixing chamber 20 instead of being disposed at the side of the furnace is disposed transversely across its top and is connected to the combustion chamber by the vertical flue 21. An air intake 22 is disposed at one end of the mixing chamber, which intake is provided with an inlet 23 communicating with the outer air, and a second inlet 24 communicating with the space within the housing 7. By means of the flap valve 25 the air for drying may be drawn entirely from the outside, entirely from the inside of the housing, or in any desired proportion from the two. The mixed combustion products and air are drawn from the mixing chamber by a suction fan 26 and then conducted through the pipe 27 to a centrally disposed manifold 28, provided with a screen 28', from which manifold lead pipes 29, in the present instance four in number, which are symmetrically disposed around the depression 9 and lead through the top 3. The pipes 27 and 29 and the manifold 28 may be heat insulated in any suitable manner, and the pipes 29 are provided with dampers 30 for regulating the flow of the drying medium. It will be seen from Figs. 1 and 2 that the discharge ends of the pipes 29 are provided with an oval flare 31 and that they lead into an annular space defined by the wall of the depression 9 and a circular depending skirt 32. A perforated diaphragm 33 extends from the bottom of skirt 32 to the wall of depression 9 and between this diaphragm and the outlet 31 of each pipe a perforated oval baffle 34 is disposed.

If desired an air distributing means such as shown and described in the above mentioned Bradley & Coffin patent may be substituted for the diaphragm 33. Ventilating pipes 35, in the present instance two in number, extend upwardly through the top 3 and roof of housing 7, said pipes being provided with dampers 36. During operation of the dryer the dampers 36 are closed, but if at any time it is desired to quickly cool the drying chamber to obtain access thereto, the dampers are opened after shutting off the flow of drying air and latex.

The space above the depression 9 is in the present embodiment enclosed by a casing 37, and a fan 38 is provided in the wall of said casing for maintaining an air pressure in the casing slightly in excess of that in the drying chamber, for a purpose to be later described. Referring to Figs. 5 and 6 it will be seen that a closure 39 is provided for the opening 10, said closure being formed of two overlapping semi-circular halves 40, which halves are provided with extensions 41 having at their ends intermeshing segmental gears 42, said gears being rigidly connected to shafts 43 and 44 journaled in a supporting bracket 45. The shaft 44 is extended upwardly through the bottom wall of depression 9 and at its upper end is operatively connected by the intermeshing gears 46 to a shaft 47 extending above the top 3, this latter shaft being actuated by means of a hand wheel 48.

The following mechanism is provided for the ready interchange of the sprayer unit for purposes of inspection, repair, etc. The upper end of the sprayer unit is provided with an eye 49 to which a cable 50 may be attached, this cable leading over a pulley 51 mounted in the movable carriage 52, the cable then extending over a pulley 53 carried by the wall of the casing 37 and thence downwardly to a winch 54. The carriage 52 is provided with rollers 55 movable on the angle irons 56 enclosing the carriage, which angle irons extend across the casing 37 and may be supported in its walls or in any other suitable manner. At a point centrally above the sprayer when in operative position one of the angle irons 56 is provided with a recess 57, with which a spring pressed detent 58 mounted on the carriage 52, is adapted to engage, and this detent may be withdrawn from the recess by the cord 59. Depending from the carriage 52 are spaced spring arms 60 on the lower ends of which are mounted lugs or detents 61, which latter are adapted to enter the tapering grooves 62 formed on opposite sides of the circular casing head of the sprayer 11.

Adjacent its bottom the drying chamber is provided in the walls 2 with opposed exhaust openings 63 (Fig. 3) for the drying medium, which openings extend entirely

from one side to the other, hinged adjustable flaps 63' being provided for varying their size. In the present instance these openings also are utilized as an inlet and outlet for a 5 movable dried latex collecting platform designated generally by the numeral 64. This device in the embodiment shown consists of a series of platform sections 65 of relatively small length but substantially 10 equal in width to that of the bottom of the drying chamber (Figs. 3 and 4). Each section is provided with a depending flexible baffle or skirt 65', which may be made of any suitable material such as canvas, for a purpose 15 to be later described. A sufficient number of platform sections 65 is used to extend entirely through the drying chamber and into the exhaust and collecting means at each end, thus forming a continuous collecting 20 surface. The sections may be connected by any suitable quick-detachable connection, and in the present instance links 66 are provided which engage adjacent openings 67 in the sections 65. Each section is 25 provided with a suitable number of casters 68 for supporting it and they may be also provided with the end castors 69 (Fig. 1) bearing against the side walls of the drying chamber to prevent binding. Any suitable 30 means may be provided for moving the platform sections through the drying chamber, and in Fig. 4 a pair of fluid operated cylinders 70 are shown at the inlet end, the pistons of which may be provided with rams 71 35 for actuating the sections. Instead of this a similar pair of cylinders 72 may be mounted at the outlet end of the drying chamber and the pistons 73 of the cylinder connected to the forward section by hooks in such manner 40 as to pull the sections through the chamber, or both sets of operating mechanisms may be used. For convenience the cylinders may be pivotally mounted as shown in Fig. 1 so that they may be swung to one side when desired. 45

It is desirable that the exhaust drying medium be maintained in contact with the latex collecting platform sections as long as possible, and that a circuitous exhaust passage 50 be provided, in order to prevent any appreciable amount of the dried latex from being carried away in the exhaust gases, and for this purpose the following exhaust and collecting mechanism is provided. A 55 cover plate 74 is pivotally mounted at 75 on a supporting bracket 76 secured to the wall 2 adjacent the exhaust opening 63, and pivotally connected to the end of the cover plate. 74 is an end plate 77 extending to the floor. A deflecting plate 78 is pivotally 60 mounted on the bracket 76 at 79, and in the position shown in full lines in Fig. 3 the plate 78 is substantially parallel to the plate 74, and it extends rearwardly of its 65 pivot to the wall 2 just above the opening

63. The outer end of the plate 78 terminates short of the end plate 77 and is pivotally connected to the plate 74 by links 80. Side walls 80' forming in effect extensions of the walls 2 of the drying chamber form 70 with the plates 74 and 77 an enclosed space communicating below the plate 78 with the exhaust opening 63. In the present instance the plates 74, 77 and 78 are each formed of six sections joined in any suitable manner. 75 Cables 81 are connected at the one end to the top plate 74 and lead over pulleys 82 mounted on the shaft 83, the other ends of the cords being connected to counterweights 84, and it will be seen that by this construction 80 the exhaust device may be swung upwardly when desired, for a purpose to be later explained. The pulleys 82 may be loosely mounted on shaft 83 in which case the exhaust device may be directly lifted by hand, 85 or if desired the pulleys may be rigidly secured to the shaft and the latter rotated by power to raise the exhaust device. Secured to the brackets 76 is a wall 85, which may be formed of any suitable material, this wall 90 being spaced from the wall 2 of the drying chamber to form an exhaust flue 86 communicating at its lower end with the space below the cover plate 74 and at its upper end with the outlets 87 leading to the open air, 95 these outlets being controlled by dampers 87'. The entire exhaust and collecting mechanism above described is duplicated at the opposite exhaust opening 63 of the drying chamber. 100

In operation the sprayer 11 is positioned in the opening 10 and suitably connected with the latex tank 13. The furnace 14 is then started, the combustion products being at first allowed to exhaust to the open air through the inlet 23 in the manner described in the above-mentioned Bradley & Coffin patent. After the furnace has become heated mixed combustion products and air are then drawn by the fan 26 from the mixing chamber 20 and supplied through the pipe 27, manifold 28, and pipes 29 to the drying chamber. The screen 28' prevents solid particles from passing into the drying chamber. Any irregularity in the distribution of 110 the drying medium may be corrected by means of the dampers 30, and as the drying medium passes through the flared outlets 31 of the pipes 29 it is spread out and is then evenly distributed around the depression 9 by means of the perforated baffles 34. It then passes through the diaphragm 33, so that a uniformly distributed slowly moving current of the heated drying medium 115 flows downwardly into the drying chamber around the sprayer 11. The sprayer 11 is put in operation in a manner similar to that described in the before-mentioned Bradley & Coffin patent, and the sprayed latex is 120 uniformly distributed in the downwardly 125 130

moving current of the drying medium as a series of relatively uniform sized particles. The drying medium may be supplied at a relatively high temperature, as the latex particles while in the upper part of the drying chamber still contain water and hence remain at a temperature around or below 212° F. As the particles approach the bottom in a dried condition the temperature of the gases has been so greatly reduced that there is no longer any danger of injury to the particles by burning or overheating. The particles fall on the platform sections 65 and the exhaust drying gases then pass out through the openings 63 into the exhaust and collecting devices. The adjustable hinged flaps 63' cause the outgoing gases to sweep directly over the collecting platform 64. It will be noted that due to the extended area of contact furnished by the platform sections 65 both in the drying chamber and within the exhaust and collecting devices substantially all of the latex particles are abstracted from the gases before leaving the collecting platform. The gases then flow up around the ends of plates 78 and between said plates and the plates 74, and finally upwardly through the flues 86 to the outlets 87. After the drying operation has continued until the desired quantity of dried latex has accumulated on the platform sections 65 the exhaust and collecting device is swung upwardly to expose the forward end section 65 in the manner shown by the dotted lines in Fig. 3. It will be noted that when in this position the rear end of the plate 78 extends downwardly into contact with the upper surface of the dried latex 88 and therefore the flow of the exhaust gases outwardly across the forward platform section 65 is prevented, the gases moving directly up into the flue 86. Hence the operatives can disconnect the forward platform section 65 without suffering any inconvenience due to the heat, and the dried latex may be removed from this section and compacted to form crude rubber or otherwise disposed of, while the empty platform section may be then returned to the opposite side of the drying chamber. The exhaust and collecting device is then lowered to the full line position of Fig. 3 and the exhaust gases resume their former path to the outlet. The exhaust and collecting device at the opposite end of the drying chamber is previously raised, an empty platform section 65 added on the preceding one and the rams 71 operated to move the entire collecting platform 64 a limited distance through the drying chamber, preferably the length of a single platform section. Instead of operating in the manner just described the bottom of the end plate 77 at the inlet side for the platform sections 65 may be cut away just sufficiently to allow entrance of a section, and each section as introduced partially pushed through so as to form a seal for the opening. By operating in this manner it will be unnecessary to manipulate the exhaust and collecting device at this side of the dryer while working. As before stated, if desired the collecting platform 64 may be pulled through by the cylinders 72 and pistons 73, or both the pushing and pulling devices may be used if desired. Any other suitable means for moving the collecting platform through the drying chamber may be substituted. The operation of the drier above described is then carried on as before, a full platform section being removed at intervals from one end while an empty one is added at the other end. It will be seen that by this construction and mode of operation an integrated deposit of the dried latex is obtained, since each section moves step by step from the exhaust and collecting device at one side through the drying chamber and the exhaust and collecting device at the other side. By reason of the construction and mode of operation previously described it is apparent that the dryer may be operated continuously and hence worked to its full capacity. However, it may be necessary at intervals to withdraw the spraying unit for repair, inspection, or for other purposes, and in order to prevent shut down of the drier for any length of time it is desirable that this withdrawal be accomplished as quickly as possible and a duplicate spraying unit immediately substituted. When it becomes necessary to exchange the spraying unit the winch 54 is operated to draw up the sprayer 11 by means of the cable 50. As the carriage 52 is held stationary by means of the detent 58 the sprayer 11 is drawn straight up until finally its rounded upper end passes between the detents 61, thus forcing apart the spring arms 60 until the detents come opposite the grooves 62, when the detents 61 snap into the grooves and further upward movement of the sprayer is prevented. The cable 50 is provided with a washer 50' which at this time engages the carriage 52 to act as a stop and prevent undue strain on the detents 61. The cord 59 is then operated to withdraw the detent 58 on the carriage 52, and it will be seen that upon the continued operation of the winch 54 the sprayer and carriage are both moved to one side of the depression 9 to the position shown in dotted lines in Fig. 5. The sprayer may then be disengaged from the detent 61 either by directly forcing apart the spring arms 60, or by partially rotating the sprayer to cause the detents 61 to ride out of the grooves 62. A duplicate sprayer may then be attached and lowered to position in place of the other. Any other suitable means for exchanging the sprayer unit

may be provided. Owing to the relatively high temperature of the drying gases flowing into the chamber around the depression 9 it will be seen that when the sprayer 11 is 5 first moved off its seat around the opening 10 the highly heated gases would tend to flow up into the housing 7, thereby rendering it practically impossible for the operatives to attend to their duties, but by the 10 provision of the casing 37 and the fan 38 a slight excess pressure is maintained within the casing 37, thereby preventing the upward flow of the drying gases. As it is of course necessary for the operatives to enter 15 and leave the casing 37 at intervals it will be seen that if it should be desired to do this while the opening 10 was free the excess pressure would be at once released and the heated drying gases could flow up. To ob- 20 viate this difficulty the closure 39 has also been provided, and as soon as the lower end of the spraying unit has passed above the opening 10 the hand wheel 48 may be operated to move the semi-circular halves 40 25 together thereby mechanically closing the opening 10. After this has been done the operators may leave and enter the casing 37 at will. If desired the casing 37 may be omitted and the air in housing 7 maintained 30 under pressure by a fan.

In the above-mentioned patent to Bradley & Coffin the drying chamber has been shown as frusto-conical in form. The taper of the side wall from top to bottom aids in preventing deposition of dried latex on the wall and also owing to its increasing cross sectional area the speed of the drying medium, which is relatively slow at its entrance, is still further reduced, thereby aiding in the 40 complete deposition of the dried latex on the floor. As the comminuted latex is discharged into the drying medium in approximately a circular form it is evident that theoretically the cross sectional form 45 for the drying chamber should also be circular, as this avoids waste of the drying medium which would occur for instance if the drying chamber were made square, as in the latter case the spaces at the corners 50 would receive practically no comminuted latex and those portions of the drying medium passing downwardly in the corners would therefore be ineffective. In addition the square corners tend to cause eddies, with 55 resultant deposition of the dried latex on the side wall. However, after the comminuted latex and drying medium have passed downward some distance in the drying chamber the drying is substantially completed, and therefore a circular shape for 60 the lower portion of the drying chamber is not so essential. In the present instance the drying chamber has been made of square shape at its bottom since this allows the movable latex collecting surface to be of a trans-

verse width equal to that of the drying chamber, and it also permits the exhaust openings, through which in the present instance the latex collecting surface also moves, to be made of the full width of the 70 drying chamber. At the same time it permits the two walls at the sides of the openings to be made of such strength as to adequately support the weight of the entire 75 drying apparatus, which is considerable. For the reasons above pointed out, however, it is still desirable that the upper portion of the drying chamber be made circular or approximately so, and therefore in the present instance this portion has been made of 80 octagonal shape, as such a shape merges very readily into the square shape of the bottom of the chamber, while at the same time allowing the chamber to be tapered from its top to its bottom. It is obvious, however, 85 that the top portion of the drying chamber need not necessarily be octagonal but may be made circular if desired, or of any other polygonal shape having a number of sides greater than that of the bottom. It is found, however, that the octagonal shape selected is sufficiently close to that of a circle to obtain all of the advantages pointed out in the before-mentioned Bradley & Coffin patent. This form also readily lends itself to the 90 beam construction of the top and the location of the depression 9.

While it is obvious that the openings 63 may be used solely for the inlet and exit of the latex collecting platform sections, and the exhaust openings for the drying medium disposed in the side walls, the construction shown allows the side walls to be made of maximum strength to support the heavy 100 weight of the drying apparatus, and by using the openings 63 for the inlet and exit of the sections they are exposed for the maximum length of time to the drying medium before the latter passes to the exhaust 105 flues, and every portion of the collecting platform from the moment a new section is added until the time that a full section is removed is in unobstructed contact with the drying medium. By the provision of the flaps 65 any tendency of the exhaust 110 gases to pass around the small gaps at the sides of the platform and then outwardly beneath the platform is prevented. It will be seen that by reason of the exhaust and collecting devices the exhaust gases are 115 never allowed to pass directly into the outside air but are furnished with a circuitous path to obtain a maximum recovery of the dried latex particles. Owing to the arrangement shown, however, the recovery of 120 the latex particles on the platform 64 is so thorough that only a minimum amount is carried beyond them, and the exhaust and collecting devices need therefore to be 125 cleaned only at relatively long intervals. 130

It will also be seen that when the exhaust and collecting devices are raised the operative is not in any way exposed to the heat of the exhaust gases and can therefore work rapidly and in comfort. By reason of the pressure casing 37 and the closure 39 the operatives at the top of the drier within the casing are also never exposed to an excessive heat during the removal or inter-
 10 change of sprayers. It is obvious that in spite of careful insulation a certain amount of heat will be freed within the housing 7, and this heat would render the housing uncomfortable to the operatives, particularly
 15 in cases where the drier is located in tropical countries. By the provision of the air intake 22, however, all or any portion of the air within the housing 7 may be drawn into the mixing chamber 20 of the furnace and
 20 fresh air drawn in through the windows or other openings of the housing 7 to take the place of the heated air. Also by reason of this construction and the direct air heating a maximum production of drying medium is
 25 obtained.

While a specific embodiment of the invention has been shown and described it is obvious that numerous modifications will suggest themselves to those skilled in the art
 30 and it is not desired to limit the invention otherwise than as set forth in the appended claims.

Having thus described my invention, what I claim and desire to protect by Letters
 35 Patent is:

1. In an apparatus for drying latex and similar material, a drying chamber, means for supplying comminuted latex and a drying medium thereto, and means movable through the chamber for obtaining an integrated deposit of the dried latex.

2. In an apparatus for drying latex and similar material, a drying chamber, means for supplying comminuted latex and a drying medium thereto, and removably connected sectional means for obtaining an integrated deposit of the dried latex.

3. In an apparatus for drying latex and similar material, a drying chamber, means for supplying comminuted latex and a drying medium thereto, removably connected sectional means exposed at all points to said medium for obtaining an integrated deposit of the dried latex, and means whereby a section may be cut off from such exposure for withdrawal.

4. In an apparatus for drying latex and similar material, a drying chamber, means for supplying comminuted latex and a drying medium thereto, and a dried latex collecting surface movable through said chamber and uninterruptedly exposed therein to the current of the medium carrying the dried particles.

5. In an apparatus for drying latex and

similar material, a drying chamber, means for supplying comminuted latex and a drying medium adjacent one end thereof, means adjacent the opposite end for exhausting said medium, and a movable dried latex collecting surface extending through said chamber and exhaust means. 70

6. In an apparatus for drying latex and similar material, a drying chamber, means for supplying comminuted latex and a drying medium adjacent one end thereof, opposed exhaust passages adjacent the other end, and a movable dried latex collecting surface extending through said chamber and passages. 75

7. In an apparatus for drying latex and similar material, an unobstructed drying chamber, means for supplying comminuted latex and a drying medium adjacent one end thereof, opposed exhaust openings adjacent the other end, and a movable sectional dried latex collecting surface extending entirely across said chamber and through said openings. 85

8. In an apparatus for drying latex and similar material, a drying chamber, means for supplying comminuted latex and a drying medium adjacent one end thereof, a circuitous exhaust passage communicating with the other end, a movable dried latex collecting surface extending through said chamber and passage, and means for short circuiting said passage when desired. 90

9. In an apparatus for drying latex and similar material, a drying chamber, means for supplying comminuted latex and a drying medium adjacent one end thereof, a dried latex collecting surface extending beyond the drying chamber, and means for varying the operative extent of said surface. 100

10. In an apparatus for drying latex and similar material, a drying chamber, means for supplying comminuted latex and a drying medium adjacent one end thereof, a dried latex collecting surface movable through and outside of said chamber, and movable means for alternatively conducting the exhaust from said chamber across or away from the portion of said surface outside the chamber. 110

11. In an apparatus for drying latex and similar material, a drying chamber, means for supplying comminuted latex and a drying medium adjacent one end thereof, an exhaust opening adjacent the other end, a movable dried latex collecting surface adapted to extend through said chamber and through and outside said opening, and means for at will deflecting the exhaust over or away from said outside portion of the collecting surface. 120

12. In an apparatus for drying latex and similar material, a drying chamber, means for supplying comminuted latex and a drying medium adjacent one end thereof, an 125

- 5 exhaust opening adjacent the other end, a movable dried latex collecting surface adapted to extend through said chamber and through and beyond said opening, a cover for the portion of said surface extending beyond the opening, said cover forming a circuitous exhaust passage, and means whereby the cover may be moved to short circuit said passage when desired.
- 10 13. In an apparatus for drying latex and similar material, an unobstructed drying chamber of increasing cross sectional area from one end to the other, means for introducing comminuted latex and a drying medium adjacent the smaller end, exhaust means for said medium, and a movable dried latex collecting surface extending entirely across said chamber adjacent its larger end.
- 15 14. In a drying apparatus, a tapering drying chamber of polygonal form at its base and merging into a polygon of a greater number of sides at its top and means movable across the base for collecting dried material.
- 20 15. In a drying apparatus, a tapering drying chamber of square form at its base, with side walls approaching a circular form at the top and means movable across the base for collecting dried material.
- 25 16. In a drying apparatus, a tapering drying chamber of square form at its base, with side walls approaching a circular form at the top, and opposed exhaust openings at the base extending the full width of the chamber.
- 30 17. In a drying apparatus, a tapering drying chamber of polygonal form at its base and approaching a circular form at its top, means for supplying comminuted latex and a drying medium thereto, opposed exhaust openings adjacent the base, and dried latex collecting means movable through said chamber in unobstructed contact with the drying medium.
- 35 18. In an apparatus for drying latex and similar material, a drying chamber, means adjacent its top for distributing finely divided latex laterally thereinto, a supply duct for a drying medium, a manifold connected thereto, and downwardly directed ducts leading from said manifold into the top of the drying chamber at symmetrically spaced points around said latex distributing means.
- 40 19. In an apparatus for drying latex and similar material, a drying chamber, means for supplying comminuted latex adjacent the top thereof, a supply duct for a drying medium, a manifold connected thereto, ducts leading from said manifold through the top of the drying chamber at symmetrically spaced points around said latex supply means, said ducts having enlarged outlets, and valves controlling the flow through said last named ducts.
- 45 20. In an apparatus for drying latex and similar material, a drying chamber, means for supplying latex thereto, means forming an enclosed space adjacent said drying chamber, a heating furnace for a drying medium disposed in said space, means for conducting the heated medium therefrom to the drying chamber, and means for at will supplying the drying medium to said furnace from within or without said space or both. 70
- 50 21. In an apparatus for drying latex and similar material, a drying chamber, means for comminuting latex therein, means forming an enclosed space above said drying chamber, an air heating furnace disposed in said space, means for conducting heated air therefrom to the drying chamber, and means for at will supplying air to said furnace from within or without said space or both. 80
- 55 22. In an apparatus for drying latex and similar material, a drying chamber, means for supplying latex thereto, means forming an enclosed space above said chamber, an air heating furnace disposed in said space, means disposed in said space for conducting heated air from the furnace to symmetrically spaced points in the drying chamber, and means for supplying air to said furnace from within or without said space or both. 90
- 60 23. In an apparatus for drying latex and similar material, a drying chamber, means for supplying latex thereto, means forming with the wall of said drying chamber an enclosed space, an air heating furnace disposed in said space, means for conducting heated air therefrom to the drying chamber, an air supply duct leading to said furnace and having openings communicating with said space and with the outside air, and a valve in said duct for controlling said openings. 100
- 65 24. In an apparatus for drying latex and similar material, a drying chamber, means for supplying latex thereto, symmetrically spaced means for supplying a drying medium thereto, and a baffle disposed in spaced relation to each of said last named supply means. 110
- 70 25. In an apparatus for drying latex and similar material, a drying chamber, means for comminuting and uniformly distributing latex therein, means for supplying a drying medium to the chamber at symmetrically spaced points around said first means, and means in the chamber for uniformly distributing the drying medium to the comminuted latex. 115
- 75 26. In an apparatus for drying latex and similar material, a drying chamber having an aperture in its top wall, a readily removable spraying unit disposed in said aperture with its discharge end in said drying chamber, a series of supply pipes for a drying medium having outlets to said chamber in spaced relation to the spraying unit, and 120
- 80 130

means for uniformly distributing the discharge from said pipes.

27. In an apparatus for drying latex and similar material, a drying chamber having 5 a central inwardly projecting apertured well in its top wall, a latex spraying device removably mounted in said aperture, means for discharging a drying medium at symmetrically spaced points around said device, 10 and means surrounding said last means for uniformly distributing and directing the medium to the sprayed latex.

28. In an apparatus for drying latex and similar material, a drying chamber, means 15 adjacent the top thereof for supplying comminuted latex and a drying medium, means adjacent the bottom whereby said medium may be exhausted, and regulable means for causing a reverse draft through said chamber when desired.

29. In an apparatus for drying latex and similar material, a drying chamber, means adjacent the top thereof for supplying comminuted latex and a drying medium, means 25 adjacent the bottom whereby said medium may be exhausted, and damper controlled ventilating stacks leading into the upper portion of said chamber.

30. In a drying apparatus, a drying chamber having an opening in the wall thereof, means whereby a distributor for the material to be dried may be interchangeably mounted in and close the opening, means for supplying a drying medium to the chamber, 35 and means for preventing egress of said medium through the opening during an interchange of distributors.

31. In a drying apparatus, a drying chamber having an opening in its top, a sprayer 40 for the material to be dried removably disposed in and closing said opening, means for supplying a heated drying medium to the chamber, and means operating by fluid pressure for preventing egress of said medium 45 through the opening upon removal of the sprayer.

32. In a drying apparatus, a drying cham-

ber having an opening in its top, a sprayer for the material to be dried removably disposed in and closing said opening, means for 50 at will exchanging said sprayer for another, means for supplying a heated drying medium to the chamber, and means for projecting an air current downwardly through said opening to prevent egress of said medium through the opening during an interchange of sprayers.

33. In a drying apparatus, a drying chamber having an apertured depression in its top, a sprayer for the material to be dried 60 removably disposed in and closing said aperture, means for supplying a heated drying medium to the chamber, and means operable from the top for mechanically closing the aperture after removal of the sprayer.

34. In a drying apparatus, a drying chamber having a depression in its top with an opening at the bottom of the depression, a sprayer for the material to be dried removably disposed in and closing said opening, 70 means for supplying a heated drying medium to the chamber, a casing enclosing the space above said depression, means for maintaining an air pressure therein in excess of that in the drying chamber, and means for mechanically closing the opening upon withdrawal of the sprayer.

35. In a drying apparatus, a drying chamber, means for supplying comminuted latex and a drying medium thereto, dried latex 80 collecting means movable through said chamber, and means for preventing escape of the drying medium beneath said collecting means.

36. In a drying apparatus, a drying chamber, means for supplying comminuted latex and a drying medium thereto, dried latex 85 collecting means movable through said chamber above the floor thereof, and flaps extending from said last means to the floor. 90

Signed at New York city, county of New York, and State of New York, this 26th day of April, 1923.

JOSEPH G. COFFIN.
